UNITED STATES PATENT OFFICE.

AIME GENDRON, OF MONTREAL, QUEBEC, CANADA.

BALING DEVICE FOR LAUNDRY.

Application filed January 15, 1926. Serial No. 31,548.

The present invention pertains to a novel baling device adapted to form bales of laundry that is washed but not ironed. The invention is particularly useful in connection with laundry of the class known as wet wash laundry.

The principal object of the invention is the provision of a device for packing laundry in the manner stated in order that it may be neatly and conveniently delivered to the customer. In the accomplishment of this object, the device comprises a box with an open top and a hinged vertical wall. Within the box is placed a sack, the upper edges of which are secured to the upper edges of the box by means of a gripping frame mounted on top of the box. After the sack has been filled, the hinged vertical wall is lowered, and the ends of the sack are drawn together by cords or similar means in order to complete the bale. The laundry is delivered in this condition, and the sack may be promptly emptied by the driver or called for at a later time.

25 The invention is fully disclosed in the following description and in the accompanying drawings in which:

Figure 1 is a perspective view of the baling box in open condition;

30 Figure 2 is a perspective view of the box closed and with the sack placed therein;

Figure 3 is a transverse vertical section corresponding to Figure 2;

35 Figure 4 is a perspective view of the bale after having been packed;

Figure 5 is a perspective view of a modified form of sack; and

Figure 6 is a perspective view of a paper lining for the sack.

40 Reference to these views will now be made by the use of like characters which are employed to designate corresponding parts throughout.

The device consists essentially of a plurality of legs 1 which serve to support a box 2 having an open top 3 and a hinged vertical wall 4 as clearly illustrated in Figure 1. The rear posts or legs 1 carry brackets 5 to which are attached hinges 6 which in turn are secured to the ends of a gripping frame 7. The rear wall of the box carries a pair of stops 7' at its upper edge in order to limit the backward movement of the hinges 6 and frame 7. This frame is constructed of angle-iron and is disposed in such a manner that the vertical

side 8 of the iron is adapted for reception within the box while the horizontal side 9 is adapted to overlie the upper edge of the box for a purpose pointed out below. 60

To one of the rear legs 1 is secured a clip member 10 which extends beyond the open side exposed by the wall 4 as illustrated in Figure 1. This clip is adapted to hold the wall in closed or raised position as illus- 65 trated in Figure 2.

The forward side of the frame 7 is provided with a pair of spaced fingers 11 adapted to co-operate with a handle 12 carried by the wall 4. The handle is pivoted 70 to the door, and the fingers 11 are in the nature of upwardly bent springs, so that these parts constitute a clamp for holding the frame upon the top of the box.

The apparatus further includes a sack for 75 lining the interior of the box and consisting of a pair of side members 13 engaged at three edges by a strip 14. The remaining edges of the side members are engaged by a shorter strip 15 which is overlapped by the 80 ends of the strip 14 as indicated by the numeral 16 in Figure 4. The strip 14 is provided with a pair of longitudinal and parallel reinforcing bands 17, and eyelets 18 which pass through the ends of these bands 85 and through the overlapped portions 16. In

In the use of the invention as thus far described, the sack is placed within the box, and the hinged wall 4 is raised to the position shown in Figure 2. The upper end of 90 the strip 14 is raised so that access to the interior of the sack may be attained. The edges of the sack are then brought over the upper edge of the box and clamped in this position by means of the frame 7 which is 95 held down by the handle 12 acting on the fingers 11. After the sack has been stuffed with laundry, the upper end of the strip 17 is brought over the top to the position shown in Figure 4, the frame 7 having previously 100 been raised. The wall 4 is now lowered so that cords 19 may be drawn through the eyelets 18 in order to tie the ends of the strip 14 together and thereby complete the bale. The laundry is delivered in this 105 manner, and the sack may be opened and emptied immediately or at a later time.

In Figure 5 is illustrated a modified form of sack designed for a higher grade of work and to present a better appearance than the 110 bale shown in Figure 4.

This sack comprises a strip 20 bent to

- 2
- form three sides, and a transverse strip 21 adapted to form the remaining three sides. The lower edge of the member 20 carries snap elements 22 adapted to co-operate with 5 complementary snap members 23 properly arranged at the lower portion of the strip 21. Flaps 24 are provided at the top of the receptacle thus formed in order to constitute a cover which is to be surmounted by the 10 upper end of the strip 21 when the latter is brought to a closing position. Finally, the ends of the strip 21 are provided with eyelets 25, so that the ends may be drawn together and the bale tightened by passing 15 cords through the eyelets in a manner described in connection with Figure 4.
- A box-shaped paper liner 26 may be placed within the sack before filling with the laundry.
- 20 While a specific embodiment of the invention has been illustrated and described, it is to be understood that various alterations in the details of construction may be made without departing from the spirit of 25 the invention as indicated by the appended claims.

Having thus fully described the invention,

what I claim as new and desire to protect by Letters Patent is:

1. In combination with a box having an open top and a hinged vertical wall, a sack adapted for insertion in said box and having top and bottom flaps constituting the top and bottom thereof, said flaps overlapping on one side of the sack and being adapted to be tied together, and a frame mounted on the top of the box and adapted to clamp the upper edges of said sack to the upper edges of said box.
2. In combination with a box having an open top and a hinged vertical wall, a sack adapted for insertion in said box and having top and bottom flaps constituting the top and bottom thereof, said flaps overlapping on one side of the sack and being adapted to be tied together, and a frame mounted on the top of the box and adapted to clamp the upper edges of said sack to the upper edges of said box, and a clamp adapted to secure 45 said frame and hinged wall together. 50

In witness whereof I have hereunto set my hand.

AIMÉ GENDRON.
